DESIGN FOR A REFRIGERATOR CABINET OR SIMILAR ARTICLE

Thomas R. Smith, Newton, Iowa, assignor to The Maytag Company, Newton, Iowa, a corporation
of Delaware

Application February 26, 1945, Serial No. 118,151

Term of patent 14 years

(Cl. D67—3)

To all whom it may concern:

Be it known that I, Thomas R. Smith, a citizen of the United States, residing at Newton, in the county of Jasper and State of Iowa, have invented a new, original, and ornamental Design for Refrigerator Cabinet or Similar Article, of which the following is a specification, reference being had to the accompanying drawing, forming a part thereof.

In the drawing:

The figure is a perspective view of a refrigerator cabinet or similar article showing my new design, the side not shown being substantially like the side shown.

I claim:

The ornamental design for a refrigerator cabinet or similar article, substantially as shown and described.

THOMAS R. SMITH.
